INDIVIDUAL CUP HEATER

Filed Nov. 9, 1929

UNITED STATES PATENT OFFICE

MONROE S. CLAWSON, OF MONTCLAIR, NEW JERSEY

INDIVIDUAL CUP HEATER

Application filed November 9, 1929. Serial No. 405,972.

The invention relates to electrical heating apparatus and has for its general object the provision of a device intended for dining or service table use or for use upon a shelf or the like in a restaurant or other eating place, the device being intended for use in the preparation of hot beverages or other liquids or employed simply for the purpose of keeping such warm after preparation in any manner.

An important object of the invention is to provide a device particularly well adapted and intended for use in holding and heating a bouillon or other cup, a feature being that the device embraces or surrounds the cup, or similar container, closely to conserve the heat and insure the application thereof to the contents in a rapid and economical manner.

A very important feature of the invention is the provision of a device of this character equipped with a novel switch device preferably of the lever type whereby the position may be readily ascertained even from a distance.

Another object is to provide a combination of this character in which the switch device is provided with means for back wiring, that is to say equipped with a portion or elements beneath which the current carrying cords may be engaged, this detail being of advantage in case the device is used on the edge of a dining or other table, shelf or the like equipped with multiple plugs for operating a plurality of electrical apparatus.

Another important object is the provision of a heater of this character which is of peculiar construction so as to concentrate the heating effect at the bottom of the cup or other container where it will do the most good.

Still another object is to provide a heating device of this character in which the cup enclosing member may be formed of refractory material with resistance coils embedded therein.

Yet another object is to provide an electric heater in which the novel and specially constructed switch assembly is detachable, readily, from the heating device itself whenever such is desirable or necessary.

An additional object is to provide a device of this character which will be simple and inexpensive to make, easy and convenient to use, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a vertical longitudinal section taken through the complete device showing a cup therein by dot and dash lines,

Figure 2 is a horizontal cross sectional view taken on the line 2—2 of Figure 1,

Figure 3 is a detail sectional view taken longitudinally through the switch device and the adjacent portion of the refractory body,

Figure 4 is a vertical cross sectional detail view taken on the line 4—4 of Figure 3,

Figure 5 is a detail horizontal section taken on the line 5—5 of Figure 3,

Figure 6 is a horizontal cross section taken on the line 6—6 of Figure 3, and

Figure 7 is a detail fragmentary cross section taken on the line 7—7 of Figure 3.

Referring more particularly to the drawings I have shown my device as comprising a shell-like body member 10 of insulating material preferably of a refractory nature and preferably shaped to conform fairly closely to the contour of the cup, dish or other receptacle containing a liquid or other substance to be heated. In the present instance this shell 10 is shown as of substantially semi-spherical shape for use in connection with and adapted to receive and enclose a cup A, shown by dot and dash lines in Figures 1 and 2, though there is no restriction as to the exact shape. As the cup is provided with a handle B this shell is represented as formed with a slot 11 for the accommodation thereof. The major portion of the shell 10 may be relatively thin but the bottom or base portion is thickened as shown at 12 and has embedded therein a coil 13 of resistance wire which will generate heat when current is

passed therethrough. This base portion 12 is prolonged at one side or extended laterally to some extent and this extended portion is peculiarly constructed for connection of a switch device therewith. As the device is intended particularly for use on a table, shelf or equivalent support, I prefer to utilize a clamp which may be formed simply as an elongated metal strip 14 having one end curled backwardly upon itself as shown at 15 and terminating in a curved end 16 adapted to engage against the underside of the shelf or table upon which the heater is placed. Embracing the strip 14 and a reduced extension 17 on the base of the shell 10 is a metallic member 18 upon which is secured a block 19 of insulating material upon the opposite sides of which are suitably secured resilient contacts 20 and 21 connected with the terminals of the resistance coil 13. The metal member 18 is preferably and is here shown as formed with downturned ends 22 projecting beyond the sides of the strip 14 for a purpose to be described.

23 In connection with this heating unit comprised by the shell 10 and resistance coil embedded in the bottom thereof, I provide a novel control switch device indicated as a whole by the numeral 23. This is represented as comprising a metal casing 24 which may be formed of any desired number of pieces secured together in any suitable manner. Located within this casing at the opposite sides thereof are blocks or pieces 25 and 26 of insulating material against the confronting faces of which are secured contacts 27 and 28 of a resilient nature adapted to engage outwardly of and against the contacts 20 and 21 respectively. A binding screw 29 is provided for the contact 28 and connected therewith is one of the current carrying conductors or cords 30. At their rear ends, that is the end most remote from the shell 10, the contacts 27 and 28 are held in spaced relation by a block 31 of insulating material. The contacts 27 and 28 are of angular shape and have upstanding extensions 32 and 32^a, the former being held by screws 33 or the like. On this extension is formed a contact arm 34 which extends toward the contact 28 but which is prevented from engagement therewith by insulating material 35 which may be a part of the block 26 or which may be a separate piece secured thereto, this detail being immaterial. I also provide a contact 36 secured as by screws 37 and 38 to the block 25 and having a curved end 39 opposite to and spaced from the contact arm 34. A second current carrying wire or cord 40 enters the switch casing and connects with the screw 38. Pivoted within the casing, as upon a transverse pin 41, is a lever 42 movable along a slot 43 in the top of the casing and adapted to occupy a position between the contacts 34 and 39 or to be out of ob-

structing relation thereto. This lever is formed of insulating material, such as fiber but it will be clear that when it is at one limit of its movement occupying a position between the contacts 34 and 39 the electrical connection to the contact 27 will be broken whereas when the lever is at the other limit of its movement the contacts 34 and 39 will engage and complete the circuit through the heating coil.

70 For securing this switch structure 23 with respect to the heating shell 10 and the metal strip 14, the latter is shown as provided with a pair of screws 44 which also pass through a clamping plate 45 disposed above the metal strip 14. The bottom wall of the casing 24 is slotted at 46 so as to be slidably engageable upon the screws in straddling relation thereto and to define flanges 47 engaging beneath the clamping plate 45. The forward portion of the casing and the blocks 25 and 26 therein are cut away as clearly shown in Figure 3 for the accommodation of the metallic member 18 and the insulating block 19 so that when the switch device, as an assembly, is in its final position with the contacts 27 and 28 embracing the contacts 20 and 21 the inner end of the casing will abut against the end of the thickened portion of the base of the heating shell.

75 Another feature is the provision at the top of the switch device of a pair of holes 48 within which may be inserted the terminal tips, not shown, of a cigar lighter or the like, the intention being that these tips be brought into engagement with the upstanding portions of the contacts 27 and 28 so that the cigar lighter would be in parallel with the heating coil.

80 The conductors or cords 30 and 40 may extend straight out, as shown in Figures 1 and 2, and are intended to carry the usual plug or other connection adapted for insertion within an electric light socket, or they may be brought back and engaged beneath the hooked ends 22 of the member 18 for back wiring, that is to say in case the device is used on the edge of a table and is to be connected with a multiple plug or socket device at the center of the table or at the back of a shelf as the case may be. When the device is used the clamp or clip 15 is engaged upon the edge of the table or shelf, the switch assembly 23 of course being secured in place with respect to the clamp and heating shell by the means above described. The cup or other article to be heated is placed within the shell 10 and the current is turned on by the simple expedient of moving the lever 42 toward the shell, thus permitting the contacts 34 and 39 to engage each other. Current will then flow from the conductor 30, contact 28, contact 21, resistance coil 13, contact 20, contact 27, extension 32, contact 34, contact 39, screw 38, and conductor 40, back to the source. The heat gen- 85

130

erated by passage of the current through the coil 13 will of course be transmitted or conducted to and through the cup or other receptacle so that the contents thereof will be heated. Owing to the particular type of switch it will be readily seen at a glance whether the current is turned on or off as the lever position will give this indication. A cigar lighter or the like may be operated at any time regardless of the position of the switch as the current therefor is taken off in advance of the switch. If for any reason it is desirable to disconnect the parts, it is merely necessary to loosen the screws 44 which will release the clamping action of the plate 45 whereupon the switch may be slid along the strip 14 toward the clamping end thereof and with the contacts 27 and 28 sliding off from the contacts 20 and 21.

From the foregoing description and a study of the drawing it will be apparent that I have thus provided a very simply constructed, inexpensive and easily operated and controlled heating device by means of which individual 25 cups or other containers may be heated for any desired purpose. It is believed that the construction, operation and advantages will be readily apparent to one skilled in the art without further explanation.

While I have shown and described the preferred embodiment of the invention, it should be understood that the disclosure is merely an exemplification of the principles involved as the right is reserved to make all 35 such changes in the details of construction as will widen the field of utility and increase the adaptability of the device provided such changes constitute no departure from the spirit of the invention or the scope of the 40 claims hereunto appended.

Having thus described the invention, I claim:

1. An electric heating device comprising a shell of insulating material having a thickened base portion, a resistant coil embedded within said base portion, a metallic supporting member mounted beneath and secured to said base portion, and a switch assembly slidably detachably mounted on said metallic member and electrically connected with said coil.

2. An electric heating device comprising a shell of insulating material having a thickened base portion, a resistance coil embedded within said base portion, a metallic supporting member mounted beneath and secured to said base portion, a switch assembly mounted on said metallic member and electrically connected with said coil, said switch assembly being enclosed within a housing having a slot in its bottom, securing elements passing upwardly through said metallic member and received within said slot, and a clamping plate 65 through which said screws pass overlying the

material at the side of the slot for clamping the switch assembly in place.

3. A device of the character described comprising a shell member of insulating material having a base provided with a resistance coil embedded therein, said base having a reduced extension, a metallic member underlying said base and formed as a clamp, a metallic member embracing the first named metallic member and the reduced extension, a block of insulating material on said second named metallic member, contacts secured on the sides of said block, and a switch assembly detachably mounted upon said first named metallic member and embodying spaced contacts slidably engaging said first named contacts.

4. A device of the character described comprising a shell member of insulating material having a base provided with a resistance coil embedded therein, said base having a reduced extension, a metallic member underlying said base and formed as a clamp, a metallic member embracing the first named metallic member and the reduced extension, a block of insulating material on said second named metallic member, contacts secured on the sides of said block, a switch assembly detachably mounted upon said first named metallic member and embodying spaced contacts slidably engaging said first named contacts, the switch assembly including a casing having a slot in its bottom extending to one end, screws carried by the first named metallic member and received within said slot, and a clamping plate carried by the screws and overlying the bottom of the casing at the sides of the slot.

5. A device of the character described comprising a shell member of insulating material having a base provided with a resistance coil embedded therein, said base having a reduced extension, a metallic member underlying said base and formed as a clamp, a metallic member embracing the first named metallic member and the reduced extension, a block of insulating material on said second named metallic member, contacts secured on the sides of said block, a switch assembly detachably mounted upon said first named metallic member and embodying spaced contacts slidably engaging said first named contacts, the switch assembly having conductors extending therefrom, and said second named metallic member having laterally extending hook portions beneath which the conductors may be engaged.

6. In a device of the character described, a switch device comprising a casing, members of insulating material disposed against the inner sides thereof, contacts secured against the confronting faces of said insulating members, said contacts being provided at one end with upstanding extensions and one having a conductor connected thereto, the other having a contact arm projecting therefrom, a third contact secured against one of

5 said insulating members and normally tending to engage said contact arm, and a lever of insulating material pivoted at one end within the casing and having its other end projecting therebeyond with its intermediate portion adapted to engage between and separate the last named contact from said contact arm.

7. In a device of the character described, 10 a switch device comprising a casing, members of insulating material disposed against the inner sides thereof, contacts secured against the confronting faces of said insulating members, said contacts being provided at one end with upstanding extensions and one having a conductor connected thereto, the other having a contact arm projecting therefrom, a third contact secured against one of said insulating members and normally tending to engage said contact arm, and a lever of insulating material pivoted at one end within the casing and having its other end projecting therebeyond with its intermediate portion adapted to engage between 15 and separate the last named contact from said contact arm, the top of the casing being formed with holes opposite said extensions adapted to receive the terminal tips of an appliance with the tips engaging said extensions.

8. An electric heating device for a drinking vessel comprising a concavo-convex shell of ceramic material having a thickened base portion, a resistance coil embedded within 30 said base portion, contacts projecting beyond said base portion and connected to the terminals of said coil, a metallic supporting member secured to the bottom of said base portion, and a switch assembly slidably mounted on said metallic member and having contacts engageable with said first named contacts.

9. An electric heating device comprising a shell of insulating material having a base portion with a resistance coil embedded 45 therein, contacts secured on said base portion and connected with the terminals of said coil, a supporting member mounted beneath and secured to said base portion and projecting therebeyond, and a switch assembly enclosed within a housing slidably mounted on said supporting member and including contacts engageable with said first named contacts.

10. An electric heating device comprising 55 a shell of insulating material having a base portion with a resistance coil embedded therein, contacts secured on said base portion and connected with the terminals of said coil, a supporting member mounted beneath and secured to said base portion and projecting therebeyond, a switch assembly enclosed within a housing slidably mounted on said supporting member and including contacts engageable with said first named contacts, and means for securing said housing

against movement along said supporting member.

11. An electric heating device comprising a shell of insulating material having a base portion with a resistance coil embedded therein, contacts secured on said base portion and connected with the terminals of said coil, a supporting member mounted beneath and secured to said base portion and projecting therebeyond, and a switch assembly enclosed within a housing slidably mounted on said supporting member and including contacts engageable with said first named contacts, said housing being provided at its sides with downwardly curved portions constituting retaining means for back wiring.

In testimony whereof I affix my signature.

MONROE S. CLAWSON.
